UNITED STATES PATENT OFFICE

WALTER G. McGAULEY, OF NEW YORK, N. Y.

DESIGN FOR A TOOTHBRUSH

Application filed July 18, 1931. Serial No. 40,572. Term of patent 14 years.

To all whom it may concern:

Be it known that I, WALTER G. McGAULEY, a citizen of the United States, residing at 112 Central Park south, New York, in the county of New York and State of New York, have invented a new, original and ornamental Design for a Toothbrush, of which the following is a specification, reference being had to the accompanying drawings, forming a part thereof.

In the drawing:

Fig. 1 is a perspective view of the brush.
Fig. 2 is a similar view looking at the opposite side of the brush.

I claim:

The ornamental design for a toothbrush, as shown.

WALTER G. McGAULEY.
